WINDING MACHINE

Peter P. Demay, Downers Grove, Ill.

Application December 9, 1935, Serial No. 53,446

6 Claims. (CL 242—9)

The invention relates to coil-winding machines.

The objects of the invention are to embody a coil-winding machine; means for registering the number of convolutions wound on the core and means for automatically stopping the winding arbor when coils of different predetermined numbers of convolutions have been wound on the core; mechanism for reciprocating the wire-guide carriage, which includes variable speed gearing which can be readily set to vary the rate of travel of the guide for evenly winding wires of different gauges; improved controlling means for the clutch mechanism of reversible gearing for reciprocating the wire-guide to more accurately control the length of the strokes of the guide-carriage; improved and readily adjustable means for varying the length of the strokes of the guide carriage; and other features for expediting the setting of the machine for coils of wire of different gauges, of different lengths and of different predetermined numbers of convolutions, which will more fully appear from the detailed description.

The invention consists in the several novel features which are hereinafter set forth and are more particularly defined by claims at the conclusion hereof.

In the drawings:

Fig. 1 is a front elevation of a machine embodying the invention. Fig. 2 is a front elevation of the mechanisms in the gear case which is shown in section. Fig. 3 is a plan of the winding mechanism, and a portion of the gear case being shown in section. Fig. 4 is an end elevation. Fig. 5 is a plan of the variable speed gearing for driving the reversible gearing which reciprocates the carriage for the wire-guides, the gear-case being shown in section. Fig. 5^a is a plan of the reversible gearing for reciprocating the carriage for the wire-guides and controlling mechanism therefor. Fig. 5^b is a section showing said carriage at the end of its in-stroke. Fig. 6 is a section on line 6—6 of Fig. 5^a. Fig. 7 is a section on line 7—7 of Fig. 5^a. Fig. 8 is a section on line 8—8 of Fig. 5^a. Fig. 9 is a section through the mechanism for driving the arbor which carries the core on which the wire is wound. Fig. 9^a is a section on line 9^a—9^a of Fig. 8. Fig. 10 is a transverse section on line 10—10 of Fig. 11. Fig. 11 is a section on line 11—11 of Fig. 10. Fig. 12 is a section on line 12—12 of Fig. 10. Fig. 13 is a section on line 13—13 of Fig. 12. Fig. 14 is a detail of the movable stop for one of the index arms of the revolution register. Fig. 15 is a section taken on line 15—15 of Fig. 14.

The invention is exemplified in a machine which comprises a driven arbor 24 for a core *a* (Fig. 3) on which wires are to be wound, and a reciprocable carriage *b*, which carries suitable guides for directing the wires from suitable sources of supply, such as reels *c* (Fig. 4) onto the core *a*. It is to be understood that the machine may be equipped with wire-guides for simultaneously winding any desired number of coils on any suitable core or cores on the arbor 10 24. The machine comprises a suitable frame 20 (Fig. 1), a supplemental base 21, and a gear case or housing 22 rigidly secured together. The carriage *b* for the wire-guides is supported on the frame 20 and in the case 22. Variable speed 15 gearing for reciprocating carriage *b*, mechanism for variably controlling the speed of travel of said carriage, mechanism for controlling the range of travel or length of the strokes of said carriage, and mechanism for controlling the number of revolutions of the arbor 24, are enclosed in gear-case 22. The core *a* on which the wire is 20 to be wound is applied to arbor 24 in any manner so as to rotate therewith to wind the wires on the core. Arbor 24 is threaded to a coupling-collar 28 (Fig. 9) which is journaled in a sleeve-section 29 and engages the inner race of a combined radial and thrust anti-friction bearing 25. A drive shaft 34 coaxial with arbor 24 is screw-threaded to the collar 28. A collar 35 is screw-threaded to shaft 34 and has an abutment for the inner race of the bearings 25, so that this race will be secured to the collars 35 and 28 and the shaft 34. The outer race of bearing 25 is clamped between a sleeve-section 30 and the 25 sleeve-section 29 which are screw-threaded to each other. Sleeve-section 30 is axially adjustable in and between plates 31 to which the sleeve-sections are respectively threaded. The sleeve-section 30 and plates 31 are mounted in a standard 30 40 45 50 55 60 65 70 75 80 85 90 95 100 105 110 115 120 125 130 135 140 145 150 155 160 165 170 175 180 185 190 195 200 205 210 215 220 cores with coils thereon. Drive-shaft 34 (Fig. 9) extends longitudinally through a driving sleeve 36, to which is secured a belt-pulley 37, which is driven by a belt 38 from any suitable source of power. A handwheel 40, integral with pulley 37, is provided, so that the sleeve 36 may be manually rotated when desired. Sleeve 36 is journaled in a combined radial thrust anti-friction bearing 41, which is carried in a two-part sleeve 42 in one of the side walls of the gear-case 22. The drive-shaft 34 is driven from the sleeve 36 under control of a clutch comprising a toothed clutch-member 43, which is slidable on and splined to shaft 34 and a clutch-member 44 keyed to the sleeve 36. A shifter-collar 45, controlled by means hereinafter set forth, is adapted to couple and uncouple clutch-members 43 and 44 to control the rotation of the arbor 25 and the core thereon.

The invention includes a revolution-register for the arbor 24, which can be readily set to stop the arbor after any predetermined number of convolutions have been wound on the coils on the core *a*. This registering mechanism is driven from the shaft 34. The register comprises an annular unit-dial 48, a rotatable index-arm 49, for dial 48, a multiple dial 50, and a rotatable index-arm 51 (Figs. 1 and 10) for dial 50. The outer dial 48 is marked, for example, with 300 indications, each for one revolution of the arbor 24. The dial 50 is marked with, say, 200 graduations, each for indicating the revolutions of arm 49 or 300 revolutions of the arbor 24. A worm-wheel 46 (Figs. 2 and 11) is fixed to shaft 34 to drive a worm-gear 47. Index-arm 49 is fixed to rotate with a shaft 54. The gearing which operates shaft 54 and index 49 from worm-gear 47 to register and indicate the revolutions of arbor 24, comprises a pair of differential planetary or epicycloidal pinions 55, 56 which are secured to rotate together and are mounted on studs carried by the worm-gear 47; a pinion 57, the hub of which is fixedly secured in a bracket 58, which is fixedly secured in the gear-case 22, and with which meshes the pinion 56; a sleeve 59, around shaft 54, and extending loosely through the hub of worm-gear 47; a pinion 60, which is integral with sleeve 59 and meshes with the pinions 55 to cause the sleeve to rotate at a low speed by reason of the difference in pitch diameters of the pinions 55, 56, the latter of which meshes with the fixed pinion 57; a clutch-member 61 fixed to the rear end of sleeve 59, which extends through and is journaled in the hub of fixed pinion 57; a coacting clutch-member 62, which is normally held in engagement with clutch-member 61 by a spring 63 and is fixed to the inner end of shaft 54. This gearing causes the index-arm 49 to register the revolutions of the arbor 24 on dial 48. The mechanism for driving the index-arm 51 to register the revolutions in multiples of 300, comprises a pair of arms 65 on a hub which is keyed to rotate with the sleeve 59 through which the unit index-arm is operated; planetary pinions 66 carried by said arms and meshing with a gear-ring 67 which is fixed to a fixed bracket 68; a gear 69, which meshes with the pinions 66 and has a hub journaled in the bracket 68; a clutch-member 70 fixed to rotate with gear 69; a coacting clutch-member 71, which is normally spring-pressed into coupled relation with member 70 by a spring 72; a hub 73 on member 71 which is fixed to index-arm 51 and is journaled in a head or plate 74 which is fitted into the front of the

gear-case 22 and carries the dials 48, 50. Gear 69 is provided with one more tooth than the gear-ring 67, so that upon each complete revolution of the sleeve 59 which drives the unit-index arm 49, gear 69 and index-arm 51 will be advanced a distance corresponding to one of the multiple-indications on dial 50 and register the multiple-indications on dial 50. The number of teeth provided on the fixed gear 69 corresponds to the number of divisions on the dial 50 and the number of teeth in gear 67 is one less and, as a result, index-arm 51 will be operated to register the revolutions of the unit-dial or, for example, the revolutions of the arbor 24 in multiples of 300. The register-mechanism is adapted to automatically stop the machine by uncoupling the clutch 43, 44, between the driving-sleeve 36 and the spindle 34. A forked lever 76 (Figs. 12 and 13) is pivoted, as at 77, to the collar 45 around clutch-member 43. Lever 76 is fulcrumed at 78 in lugs projecting from a bracket 79 which is fixed in the gear-case 22.

A block 80 has trunnions 80^a pivotally held in the upper end of lever 76. A double arm 83 is fixed to a shaft 84. The lower end of arm 86 is pivotally connected to operate lever 76 to positively uncouple clutch 43, 44 by a link-pin 81, which is slidably mounted in block 80 and has trunnions at its rear end which are pivoted in the lower end of lever 83. An abutment-nut 81^a on the front end of link-pin 81 engages the front of block 80, and a spring 81^b is interposed between the block and arm 83. When arm 86 is shifted in one direction, it will positively rock lever 76 to uncouple clutch 43, 44. When said arm is moved in the opposite direction, it will, through spring 81^b, yieldingly shift lever 76 to couple the clutch-members. A spring 90 between arm 83 and gear-case 22 is applied to rock shaft 84 so abutments 88 will bear against clutch-members 71, 62, and to rock the shaft to uncouple clutch 42, 43 when the abutments 88 pass into notches 89.

A pair of trip-arms 86, 87 are fixedly secured to the shaft 84 of arm 83 and each of said arms is provided at its free end with an abutment 88. Clutch-member 62, through which the unit index-arm 49 is driven, and clutch-member 71, through which the multiple index-arm 51 is driven, are each provided with a notch 89. Trip-arm 87 rides on the periphery of clutch-member 71 and trip-arm 86 rides on the periphery of clutch-member 62. When the notches 89, in the course of the rotation of clutch-members 71, 72, register with the abutments 88 on trip-arms 86, 87, the abutments will drop into the notches and said arms will be shifted to rock shaft 84 and arm 86 to uncouple the clutch 43, 44. When the abutments 88 of trip-arms 86, 87 are lifted by the periphery of clutch-members 71, 62, shaft 84 will be held in position to hold the clutch-members 43, 44 coupled.

The number of revolutions of the spool spindle or convolutions of wire on the spool for each winding operation before the machine is automatically stopped, may be varied to any desired predetermined number of revolutions within the range of the indicator-dials. The clutch-member 62 may be rotatably set to bring its notch 89 any desired distance from abutment 88 of arm 70 86 when member 62 is uncoupled from its coacting member 61. Clutch-member 71 may be rotatably adjusted to bring its notch 89 any desired distance from the abutment 88 on trip-arm 87 when member 71 is uncoupled from its coacting 75

member 70. A stop 49^a is adjustably secured by screws in an undercut channel 81 in the front of dial-plate of head 74. This stop (Figs. 14 and 15) carries a pivoted spring-pressed dog 49^b, which permits the index-arm 49 to slip under the stop while it is being operated in one direction by the gearing. A stop 51^a (Fig. 11) is adjustably secured in an annular channel 82 in the hub or plate 77. These stops can be set at any of the indications on the respective dials according to the desired number of revolutions of the arbor 24. When the index-arms 49, 51 of the register are at the zero indications on the dials 48, 50, respectively, the notches 89 in clutch-members 62, 71 will be positioned to trip the controlling mechanism for the clutch 43, 44. To set the machine for any desired number of convolutions of wire on the core a, the operator will set the stops 49^a and 51^a at points corresponding to the number of convolutions desired. When the index-arms are moved against the stops, the machine will operate through clutch 43, 44 until the index arms both reach the zero indication, at which time the notches 89 will both be positioned to trip the arms 86 and 87 and uncouple clutch 43, 44.

When a change in the setting of the index-arms 49, 51 is desired, they are uncoupled from their driving mechanism. For this purpose, clutch 70, 71, through which index-arm 51 is operated around dial 50, and clutch 61, 62, through which index-arm 49 is operated around dial 48, are uncoupled and locked in uncoupled position, so the index-arms will be rotatable independently of their driving mechanism. The mechanism for this purpose comprises a handle 216 (Figs. 1, 10 and 12) on a shaft 217, which is journaled in the gear-case; a bevel-pinion 218 fixed to shaft 217; a bevel-gear 219 meshing with gear 218 and fixed to a stud 220, which is journaled in a plate 221, which is fixed to the bracket 79; a pair of oppositely extending arms 222 (Fig. 12) fixed to shaft 220; a pair of slides 223 pivoted to arms 222 and slidably mounted on the bottom of plate 221, a forked lever 224 pivoted to bracket 58 and adapted to engage clutch-member 62 to disengage it against the force of spring 63 from driving-member 61; a similar lever 225 pivoted to bracket 68 and adapted to disengage against the force of spring 72 the clutch-member 71 from the driving-member 70. Slides 223 are provided with hooks 226 for engaging the upper ends of levers 224 and 225 when the handle 216 is turned to move said ends together and uncouple said clutches. A cam 227 (Figs. 2, 10 and 12) is fixed to the shaft 217 of handle 216 to engage an arm 228 which is fixed to the shaft 84 of the devices for operating the trip-arms 86, 87 (Fig. 13), which control the starting and stopping of the machine. When the handle 216 is shifted from its normal position, shown in Fig. 1, the index-arms of the revolution-counters will be uncoupled from their driving mechanism and will be free for settings at different points on their dials.

The reciprocable carriage b is provided with arms 95 for separately guiding wires longitudinally of the core, so that the convolutions will be closely and evenly wound. Any desired number of these arms, according to the number of coils to be wound during each operation, may be provided. The carriage b comprises a pair of rods 96 and 97, which are slidably mounted in a wall of the gear-case 22 and a fixed bracket 98; a crosshead 94 in the gear-case 22 in which the inner ends of rods 96 are fixedly secured; a pair

of brackets 99 fixed to rods 96, 97; and a shaft 100 mounted in the upper end of brackets 99 to which the guide-arms 95 are individually clamped for relative adjustment. The shaft 100 is pivotally mounted in brackets 99, so the arms 95 can be swung upwardly to provide access to the coils on the core when desired, and is provided with suitable locking means, such as a screw-wheel 101, for securing shaft 100 and arms 95 in their operative position. Grooved guide-wheels 102 are carried at the free ends of arms 95 for guiding the wire from reels c (Fig. 4) which are usually placed in the rear of the machine.

The mechanism for reciprocating the carriage b comprises a shaft 105 (Figs. 6 and 7) which is journaled in a bracket 106 in the gear-case 22, and an antifriction combined radial and thrust-bearing 108; a screw 107 which is threaded to a nut 109, which is fixedly secured to the carriage-head 94 and against rotation by a boxing 110, which is secured to said head; and reversible gearing for rotating the screw 107 in opposite directions to reciprocate the carriage b. This reversible gearing comprises a shaft 111, which is journaled in a bearing-bracket 112 (Fig. 6); a gear 113 fixed to and for driving said shaft 111; a bevel gear 114 fixed to shaft 111 and provided with a clutch-member 115; an oppositely facing, bevel gear 116, which is loosely mounted on the shaft 105 and is provided with clutch-teeth 117; an intermediate bevel gear 118 journaled on a fixed stud 119 and meshing with gears 114, 116, and a clutch-sleeve 120, which is splined to and slidably on the shaft 105 and is provided with clutch-teeth at its opposite ends to mesh with the clutch-members 115 and 117, respectively. When the clutch-sleeve 120 is coupled to the bevel-gear 114, shaft 105 and screw 107 will be driven in one direction directly from the gear 114. When the sleeve 120 is disengaged from the gear 114 and engaged with clutch-teeth 117, shaft 105, screw 107 will be driven in the opposite direction through intermediate gear 118, bevel gear 116 and clutch-sleeve 120. The sleeve 120 is automatically shifted and controlled by mechanism herein-after described to reciprocate the carriage for the wire guides.

The invention contemplates variation of the relative speed of travel of the carriage b according to the gauge of the wire to be wound on the core. For this purpose, variable speed mechanism is provided whereby the speed of the mechanism, including screw-shaft 107, may be varied so that the travel of the carriage during each revolution of the spools, will correspond substantially to the gauge of the wire being wound on the core. This mechanism comprises (Figs. 2 and 5) a gear 122 (Fig. 2) secured to the inner end of the shaft 34, which drives and rotates with the arbor 24; a gear 123, which meshes with gear 122; a pinion 125, which is connected by a sleeve 124 with gear 123; a gear 126, meshing with gear 123 and loosely mounted on a shaft 129, which is journaled in suitable bearings in the gear-case; a gear 130, which meshes with pinion 125 and 126, 127 to drive shaft 129 at two different speeds; a gear 132 fixed to the inner end of shaft 129; a gear 133, which meshes with gear 132 and is fixed to a shaft 134, which is suitably journaled in the gear-case 22; a clutch-sleeve 135 which is splined to and rotatable with shaft 134; gears 136 and 137, which are loosely mounted on shaft 135.

134, adapted to be separately coupled to and driven by said shaft through sleeve 135, and are of different diameters; a gear 138, which meshes with gear 136 and is fixed on a sleeve 139; a gear 140, which meshes with gear 137; gears 141 and 142 of different diameters, which are fixed to rotate with gears 138, 140; a set of gears 143, 144 and 145, which are fixed to a sleeve 146, which is splined to, and slideable on, a shaft 147, so that gear 143 may be slipped into engagement with gear 142, gear 144 may be slipped into engagement with gear 141, and gear 145 may be slipped into engagement with gear 138 to drive shaft 147 at different speeds relatively to shaft 134; a sleeve 148, which is splined to, and slideable on, shaft 147 and has affixed thereto gears 149, 150 and 151; a sleeve 152, which has affixed thereto a gear 153 adapted to mesh with gear 146, a gear 154 adapted to mesh with gear 150, and a gear 155 adapted to mesh with gear 151; and an idler gear 156 (Fig. 6), which meshes with gear 113 on shaft 111. A fork 157 is adapted to shift clutch-sleeve 131 between gears 126 and 130 and is fixed to a rock-shaft 158, which extends through the front of the gear-case 22 and is provided with a handle 159 whereby the fork may be shifted to couple the shaft 129 so it will be driven at different speeds by gear 130 or pinion 126 to vary the speed of the entire gear-train driven from shaft 129. A forked lever 160 is adapted to shift the clutch-sleeve 135 to couple gear 136 or gear 137 to the shaft 134 and is pivoted in a bracket 161 in the gear-case. A handle 162, pivotally mounted in the front of the gear-case, operates a lug or arm 163 (Fig. 5) to shift lever 160. By shifting the clutch-sleeve 135, the set of gears 138, 141, 142, 140 may be alternately driven at two different speeds to correspondingly vary the speed of the gear-train driven thereby. A fork 164 is provided for shifting sleeve 146 and gears 143, 144, 145 on shaft 147 for engagement, respectively, with gears 142, 141 and 138, and is fixed to the inner end of a shaft 165, to the front end of which a handle 166 is fixed. This handle may be set in any of three positions for respectively engaging the gear-pairs. By this, the shaft 147 may be driven at three different speeds relatively to shaft 134 to correspondingly vary the gear-train driven by shaft 147. A fork 167 for shifting sleeve 148 and gears 149, 150 and 151, is fixed to the inner end of a rock-shaft 168, to the front end of which a handle 169 is secured, so that the sleeve 152, which carries gears 153, 154, 155, may be driven at three different speeds relatively to shaft 147, to correspondingly vary the speed of gears 156, 113 and shaft 111, through which the carriage for the wire-guides is shifted longitudinally. By means of various settings of the handles 159, 169, 162, 165, or any permutations thereof, the speed of travel of the wire-guide carriage relatively to the speed of rotation of the spools on which the wire is being wound, may be varied to correspond to the different gauges of wire used in winding coils for different uses or purposes. This exemplifies variable speed mechanism for this purpose, which is readily controllable so that the machine may be quickly set for winding different gauges of wire on the spools.

The machine is adapted for winding coils of different lengths. For this purpose, mechanism is provided for automatically shifting the clutch-sleeve 120 to impart strokes of variable length to the carriage *b* according to the length of the coils desired. This mechanism comprises a worm 171, which is fixed to the shaft 105 (Figs. 6, 7 and 9a); a worm-gear 172 engaged by said worm and fixed to a shaft 172a, which is journaled in an up-standing lug on bracket 106; a pinion 173 fixed to rotate with shaft 172a and a worm-gear 172; a gear 174 (Figs. 5a and 8); a shaft 175 journaled in a bracket 175a fixed in the gear-case 22, and to which gear 174 is fixed; a clutch comprising a member 176 fixed to shaft 175 and a coacting member 177, which is connected to drive a sleeve 178 which is journaled in a plate or head 179 in the front of the gear-case 22; an index-arm 180, which is fixed to rotate with sleeve 178 and member 177; a cam 181, on the back-face of clutch-member 177 and adapted to be rotatively adjusted by the arm 180; and a cam 182, which is fixed to a hub which is fixed to rotate with shaft 175. Cams 182, 181 rotate with the driven shaft 175 to control the reversible gearing for reciprocating the wire-guide carriage. Cam 181 is rotatively adjustable relatively to cam 182 to vary the length of the strokes of said carriage. A shifter-collar 183 (Fig. 5a) is adapted to slide clutch-sleeve 120 into engagement with either of the gears 114, 116 to drive shaft 105 and screw 107 in opposite directions. A lever 184, for shifting collar 183, is fulcrumed at 185 and is provided with an abutment 186 (Fig. 5a). A pair of rods 187 are adjustably secured to projecting lugs on collar 183, are slideable in and through bracket 106, and are cross-connected by a bar 188. Springs 189 are applied between bracket 106 and collars 189a, which are shouldered against, and slideable in, the crossbar 188 to exert pressure to the right on crossbar 188 and shift, through rods 187, collar 183 and clutch-sleeve 120 to engage said sleeve and bevelled gear 116 when the lever 184 is released by the controlling mechanism for said lever. Collar 183 is reversely shifted to engage sleeve 120 and bevelled gear 114, by a pair of abutment collars 200, which are carried by a pair of rods 200. The outer ends of rods 200 are fixedly secured in the crosshead 94 of the carriage *b*, so they will reciprocate with the carriage and their inner ends are slideable through collars 189a in crossbar 188 and are slideable in the bracket 106. Springs 190 are interposed between washers 190a, which bear against collars 200a and the crosshead 94. Collars 200a are fixedly connected to rods 200. During the instroke of the crosshead 94, collars 200a engage the collars 189a to relieve the crossbar 188 from the pressure of springs 189. Thereafter, the spring-pressed washers 190a engage the crossbar 188 to apply the pressure of springs 190 to said crossbar, so that collar 183 will be shifted to the left as soon as lever 184 is released by its controlling mechanism. This spring-pressed means for shifting the clutch-sleeve 120 of the reversible gearing exemplifies a construction by which spring-pressure will be applied to said sleeve before the controlling mechanism releases the lever 184 for its respective movements for a quick and accurate timing of clutch-sleeve 120 in the reciprocations of the carriage *b*.

An abutment-arm 205 (Figs. 5a, 8 and 9a), controlled by rotatable cam 182, and an abutment-arm 204, controlled by cam 181, control the movements of lever 184 and clutch-sleeve 120 at the ends of the in and out-strokes of the carriage *b*. These abutment-arms alternately lock and release said lever under control of said cams. Cam 182 is fixed on a hub which rotates with the shaft 175 which is driven by gear 174 from the reversible shaft 105. Cam 181 is on clutch-member 177, which is secured to arm 180 and is driven by 75

clutch-member 176 on shaft 175. The reverse movements of shaft 185 conjointly rotate shaft 175 and cams 182 and 181 in opposite directions to cause the cams to alternately shift the rocker-arms 204, 205 to release lever 184 for the movements of clutch-sleeve 120, and to lock it in shifted positions at the end of the in and out-strokes of the carriage b. Cam 182 engages an arm 208 on a rocker 202, to which abutment-arm 205 is secured. A spring 210 is applied to rocker 202 to press arm 208 towards the face of cam 182. Cam 181 on member 177 engages an arm 208 on rocker 202, which is connected by a shaft 202^b to the abutment-arm 202. A spring 211 is applied to rocker 202 to shift abutment-arm 204 when lever 184 is shifted into one of its alternate positions. Adjustable stops 201 are provided to limit the movement of lever 184. Shaft 202^b is journaled in bearing-brackets 203.

20 Near the end of each in-stroke of the carriage b, the spring-pressed washers 190^a, which reciprocate therewith, will, after collars 200^a have compressed springs 189, engage crossbar 188, to shift the collar 183 to engage clutch-sleeve 120 and bevelled gear 114 when cam 182 rocks arm 208 and swings abutment-arm 205 clear of abutment 186 on lever 184. Simultaneously, abutment-arm 204 will be rocked by its spring 211 to lock lever 184 to keep the clutch-sleeve so engaged 30 during the out-stroke of the carriage. The out-stroke of the carriage will continue until cam 181 engages arm 208 and shifts abutment-arm 204 to clear abutment 186, at which time lever 184 will be released, so that springs 189 will, through 35 crossbar 188 and rods 187, shift sleeve 120 to engage bevelled gear 116 and, thereupon, the in-stroke will commence. Simultaneously, spring 210 will swing arm 205 into position to engage abutment 186 on lever 184 to hold sleeve 120 thus 40 engaged. The in-stroke of the carriage will continue until the washers 190^a exert pressure to the left on crossbar 188 and cam 182 rocks abutment-arm 205 to release lever 184, so that sleeve 120 will again engage bevelled gear 114. These 45 reciprocations will continue until the machine is automatically stopped at register-controlled clutch 43, 44.

The invention includes mechanism for readily varying the strokes of the carriage by rotatably 50 adjusting cam 181 relative to cam 182 to vary the timing of periods of engagement of driving-sleeve 120 with gears 114, 116, respectively. An index-arm 212 (Figs. 1 and 8) is keyed to and rotates with shaft 175 and cam 182. Index-arms 55 212 and 180 are rotatable around a dial 214 on the front of head 179. A nut 213 is adapted to be tightened, so that arms 212, 180 and clutch-members 176, 177 will be locked together to rotate with shaft 174. The spacing between 60 index-arms 180 and 212 and corresponding spacing between cams 182 and 181, will control the lengths of the stroke of carriage b. When a change in the length of the stroke is desired, the operator will loosen nut 213, so that index-arm 65 180, which is fixedly connected to clutch-member 177, which carries cam 181, can be rotated relatively to its coaxing clutch-member 176 to effect a different setting between the index-arms and a corresponding variation in the periods between 70 the movements of the clutch-sleeve 120 of the reverse gearing for reciprocating carriage b. When nut 213 is loosened, spring 215 will separate clutch-member 177 from member 176, so that the operator can freely adjust cam 181 relatively 75 to cam 182. After this setting has been effected

as desired, nut 213 will be tightened to maintain the desired stroke-lengths of the carriage b until change for a variation in the length of the coils is desired. During the operation of the machine, index-arms rotate together and the graduations 5 between arms 180, 212 indicate the length of the carriage-stroke for which the machine is set. This exemplifies means which is easily and quickly adjustable to vary the length of the carriage-strokes.

The operation of the machine will be as follows: The operator will place a core of any suitable type on the spindle 24 by sliding the tail-stock 27 into position to permit the core to be secured thereon and then replacing the tail-stock 15 in its operative position. The ends of the wires from the supply reels c will then be directed around the guide-sheaves 102 and secured on the core. The operator will relatively set the indicator-arms 180, 212 on the dial 214 to correspond 20 to the stroke of the guide-wires desired, according to the length of the coils desired. In this setting, cam 181 will be rotatably adjusted relatively to cam 182 to vary the timing or periods between the shifting movements of clutch-sleeve 25 120 of the reverse gearing for operating the guide-carriage. After the setting has been made, nut 213 will be tightened to fix the cams in their relative position. The operator will also, by the selective settings of the control levers 169, 166, 30 162 and 163, adjust the speed-change gearing which drives the reversible gearing for reciprocating the guide-carriage to regulate the speed of movement of the carriage according to the gauge of the wire to be wound on the core. The stops 35 49^a and 51^a of the revolution-register will be adjusted according to the number of convolutions of wire to be wound on each coil. This will adjust the clutch-members 62, 71 (Fig. 10) to bring the notches 89 therein so that after the desired predetermined number of revolutions of the spindle, the driving clutch 43, 44 for the machine will be uncoupled. The stops 49^a, 51^a will be set away from the zero indicators on dials 48, 50, according 40 to the number of revolutions of the core spindle 45 desired. In making this setting, lever 216 will be shifted to uncouple clutch-members 62, 71, through which the index-arms 49, 51 are driven, so that said arms can be moved independently 50 of their driving mechanism. The index-arms will be shifted against their respective stops and the handle 216 will be returned to its normal position to release clutch-members 62, 71 and couple the arms 49, 51 to their driving mechanism. The notches 89 in said clutch-members 55 will then be rotated from the zero point to correspond to the number of revolutions of the core desired. As these clutch-members are rotated, the driving-clutch 43, 44 for the machine will be coupled to start the machine. The operation of 60 the machine will continue until the notches 89 on members 62, 71 reach the zero position, when the trip-arms 86, 87 will enter the notches and automatically uncouple the driving clutch and stop the entire machine.

The invention exemplifies an improved coil-winding machine which can be quickly set to vary the number of convolutions of wire on each coil, the speed of travel of the wire-guide to conform to different gauges of wire to be wound on 70 the core, and the length of the stroke of the wire-guides to correspond to the different lengths of the area of the cores which are covered by the windings. This makes it possible to economically produce coil-windings with any number of con- 75

volutions, different gauges of wire and different lengths of spools.

The invention is not to be understood as restricted to the details set forth, since these may 5 be modified within the scope of the appended claims, without departing from the spirit and scope of the invention.

Having thus described the invention, what I claim as new and desire to secure by Letters Patent is:

1. In mechanism for controlling the operation of a power-driven machine for continuously winding a series of layers of wire on a core, the combination of a clutch for controlling the operation 15 of the machine, a register for the number of windings including unit and multiple indicators, mechanism for driving the register from the clutch, means for selectively setting the indicators according to different selected total numbers 20 of windings desired, and means controlled by the setting of the indicators for actuating the clutch to positively stop the machine.

2. In mechanism for controlling the operation of a power-driven machine for continuously 25 winding a series of layers of wire on a core, the combination of a clutch for controlling the operation of the machine, a register for the number of windings including unit and multiple indicators, mechanism for driving the register from 30 the clutch, means for selectively setting the indicators according to the different selected total numbers of windings desired, and means, controlled by the setting of the indicators for actuating the clutch to positively stop the machine, 35 and for starting the machine.

3. In mechanism for controlling the operation of a power-driven machine for continuously winding a series of layers of wire on a core, the combination of driving mechanism for the machine, a 40 register for the number of windings including indicators for unit and multiple indicators, means for driving the indicators from said driving mechanism, adjustable stop-means for selectively setting the indicators for the different total numbers of windings desired, and means, controlled by the setting of the indicators and the stop-means, for stopping said mechanism.

4. In mechanism for controlling the operation

of a power-driven machine for continuously winding a series of layers of wire on a core, the combination of driving mechanism for the machine, a register for the number of windings including indicators for unit and multiple indicators, means for driving the indicators from said driving mechanism, adjustable stop-means for selectively setting the indicators for the different total numbers of windings desired, means, controlled by the setting of the indicators and the stop-means, for stopping said mechanism, friction clutches between the indicators and the indicator driving means, and means for releasing the friction clutches to permit the indicators to be set against the stop-means in starting the 10 mechanism.

5. In mechanism for controlling the operation of a power-driven machine for continuously winding a series of layers of wire on a core, the combination of driving mechanism for the machine, a register for the number of windings including indicators for unit and multiple indicators, means for driving the indicators from said driving mechanism, adjustable stop-means for selectively setting the indicators for the different 20 total numbers of windings desired, means controlled by the setting of the indicators against the stop-means for stopping said mechanism, friction clutches between the indicators and the indicator driving means, and means, comprising 25 a lever, for releasing the friction clutches to permit the indicators to be set against the stops in starting the mechanism.

6. In mechanism for controlling the operation of a power-driven machine for continuously winding a series of layers of wire on a core, the combination of driving mechanism for the machine, a register for the number of windings including indicators for unit and multiple indicators, means for driving the indicators from said driving mechanism, adjustable stop-means for selectively setting the indicators for the different total numbers of windings desired, and means controlled by the setting of the indicators against the stop-means for stopping said mechanism, said control means being adapted to start said mechanism, by the shift of the indicators toward said stops. 35

PETER P. DEMAY.
